CLAIM

The ornamental design for a medical apparatus, as shown and described.

DESCRIPTION

FIG. 1 is a top, right, front perspective view of a first embodiment of a medical apparatus showing our new design;

FIG. 2 is a top, left, front perspective view thereof;

FIG. 3 is a top, left, rear perspective view thereof;

FIG. 4 is front elevation view thereof;

FIG. 5 is a left elevation view thereof;

FIG. 6 is a right elevation view thereof;

FIG. 7 is a rear elevation view thereof;

FIG. 8 is a top plan view thereof;

FIG. 9 is a bottom plan view thereof;

FIG. 10 is a top, right, front perspective view of a second embodiment of a medical apparatus showing our new design;

FIG. 11 is a top, left, front perspective view thereof;

FIG. 12 is a top, left, rear perspective view thereof;

FIG. 13 is front elevation view thereof;

FIG. 14 is a left elevation view thereof;

FIG. 15 is a right elevation view thereof;

FIG. 16 is a rear elevation view thereof;

FIG. 17 is a top plan view thereof; and,

FIG. 18 is a bottom plan view.
